UNITED STATES PATENT OFFICE.

ALEXANDER HOLLEY OLMS TED, OF BOWDON, ENGLAND.

VOLTAGE-REGULATOR FOR ELECTRIC GENERATORS.

1,162,506.

Specification of Letters Patent. Patented Nov. 30, 1915.

Application filed January 28, 1913. Serial No. 744,646.

To all whom it may concern:

Be it known that I, ALEXANDER HOLLEY OLMS TED, a citizen of the United States of America, and a resident of Bowdon, in the county of Chester, England, have invented a new and useful Improvement in Voltage-Regulators for Electric Generators, of which the following is a specification.

This invention relates to voltage regulators of the kind adapted to vary the excitation of an electric generator or of its excitors, so as to maintain a constant voltage on the generator terminals and is an improvement in or modification of the voltage regulator described in the specification of application for British Letters Patent No. 28747 of 20th December 1911.

In the regulator described in the above mentioned specification, a resistance in series with the field magnet winding of the generator or its exciter is arranged to be short circuited through two contacts operated by a relay magnet and a short-circuit around the magnet is made and broken by another pair of contacts one of which is carried on a vibrating arm whose rate of oscillation is caused to vary automatically in accordance with variation in voltage of the generator. Said vibrating arm is caused to oscillate by means of an electro-magnet the circuit of which is made and broken by two contacts, one of which is carried on said arm and the other on another arm, the position of which varies in accordance with the voltage of the generator to be controlled.

According to the present invention the contact with which the contact on the vibrating arm co-operates is fixed and the construction and arrangement of the regulator are such that the use of a spring for causing these contacts to close when the operating magnet of the vibrating arm is de-energized is dispensed with.

The invention further comprises certain improvements in the construction of the regulator.

In order that the nature of the invention may be clearly understood, a voltage regulator embodying the same will now be described with reference to the accompanying drawings in which—

Figure 1 is a front elevation and Fig. 2 a side elevation of a preferred construction of one part of the apparatus. Fig. 3 is a front elevation and Fig. 4 a side elevation of a preferred construction of another part of the

apparatus, and Fig. 5 is a diagrammatic view showing the electrical connections of the various devices with the exciter which excites the field magnets of the machine supplying current to the circuit to be regulated.

Referring now to Figs. 1 and 2, a magnet hereinafter referred to as the main magnet which is energized directly or indirectly from the generator the voltage of which is to be controlled, is provided with a coil 1 and two cores 2, 3, of which the core 2 is mounted on an arm or lever 4 pivoted below the magnet the other core 3 being adjustably supported within the coil 1 from a bracket 5 by means of the screw 6 the cores 2 and 3 are provided with axial saw cuts 7 to reduce eddy currents therein. The pivoted lever 4 is supported by a spring 8 from a bracket 9 the tension of the spring being adjusted by means of the screw 10 in the ordinary way and it will be readily seen that if the coil 1 is supplied with current and the voltage at the terminals thereof is maintained constant the spring can be adjusted so that the lever 4 will be maintained in equilibrium in any position. 11 is a dash pot carried on a fixed bracket 12 the piston of which is pivotally attached to a flat spring 13 secured to the lever 4. The object of this spring is partially to reduce "humming" and partly to assist the lever 4 and core 2 to adjust themselves to any position which they are caused to take by variation in the pull of the main magnet.

Another magnet hereinafter termed the vibrator magnet is provided with a coil 14, a core 15, a fixed pole piece 16 and an adjustable pole piece 17. The armature which co-operates with the adjustable pole piece is indicated at 18 and consists of a thin strip of iron mounted on a lever 19 which in turn is mounted on a shaft 20 being insulated therefrom by a mica sleeve 21. The shaft 20 is arranged to rotate in a bearing formed by the screws 22, 23 in a fixed bracket 24. The arm 19 carries at its free end a contact 25 preferably formed of silver which co-operates with a similar contact 26 mounted on a spring 27 secured to a fixed bracket 28. Carried by the lever 19 is an arm 29 on which is mounted a contact 30, said contact co-operates with a contact 31 mounted on a pivoted lever 32 the pivot 33 of this lever being carried in the bracket 24 by screws 22 and 34. A spring 35 one end of which is adjustably connected to the

bracket 24 has its other end connected to the lever 32 and holds said lever lightly against a stop 36 mounted in a bracket 37 attached to the lever 4.

5 Referring now to Figs. 3 and 4 which show the relay magnet which operates the contacts for short-circuiting the resistance in series with the generator or its exciter, 38, 39 are two coils connected in series and 10 mounted respectively on the cores 40 and 41 the lower ends of which are connected by an iron piece 42 which is carried on a bracket 43 secured to a suitable base 44. The armature of the magnet is indicated at 15 45 and is carried by an arm 46 pivoted at 47. Said armature carries an adjustable contact 48 preferably of silver which cooperates with a similar contact 49 carried by an arm 50 mounted on a fixed bracket 20 51 a spring 52 tending to maintain the two contacts 48, 49 in connection.

The magnets, brackets and other fixed parts of the apparatus above described are conveniently mounted on the same base 25 which may be a panel of a switchboard for example as indicated at 44 in Figs. 2 and 3.

Referring now to the diagram Fig. 5, which shows the electrical connections of the various parts, the coil 1 of the main 30 magnet is connected by wires 72, 73 across two of the terminals of a 3-phase alternator 68 supplying mains 69, 70, 71, the voltage of which is to be regulated, the field winding 74 of the alternator 68 being connected 35 across the brushes of the exciter 58. Transformers or suitable resistances may, of course, be interposed between the magnet and the circuit if necessary. The coil 14 of the vibrator magnet is connected by a 40 wire 53 to one pole of a storage battery 54, the other pole of which is connected through wire 55, lever 19, contacts 25 and 26, spring 27 and wire 56 to the other terminal of the coil 14. A resistance 57 serves to minimize 45 the spark which occurs on breaking the connection between the contacts 25, 26. The coils 38, 39 of the relay magnet are energized from the exciter the armature of which is indicated at 58, the current passing 50 by a wire 59 through the battery 54, wire 55, contacts 30 and 31, wire 60, relay coils 38, 39, wire 61 and resistance 62 to the negative terminal of the exciter. Resistance 63 connected between the wires 55 55 and 60 serves to minimize the spark which occurs on breaking the connection between the contacts 30 and 31. The field magnet coil of the exciter is indicated at 64 and in its field circuit is arranged a resistance, one 60 portion 65 of which has its terminals connected to the relay contacts 48 and 49 so as to be short-circuited when the relay coils 38 and 39 are not energized.

The operation of the regulator is substantially as follows:—The battery 54 will con-

tinually receive a charging current from the exciter armature 58 through the resistance 66 and the current from the exciter which passes through the relay coils 38 and 39 will also assist in charging the same. The vibrator magnet with its armature 18 and the cooperating contacts 25 and 26 in conjunction with the battery 54 will operate to cause the arm 19 to vibrate with a regular frequency after the manner of an electric 70 trembling bell and thus cause contact 30 to vibrate with a perfectly definite travel and frequency of vibration, the weight of lever 32 and the force of the spring 35 being so small compared with the mass of the lever 30 75 that the fact of the contacts 30 and 31 being in or out of engagement will not affect the vibration of the lever 19. The circuit of the relay coils 38 and 39 is made and broken by the contacts 30 and 31 and the length of 80 time per vibration of the lever 19 that these contacts remain in engagement will be determined by the position of the stop 36 which is carried on the lever 4. The position of this lever and of the stop which it carries will 85 vary in accordance with variations in the voltage applied to the terminals of the main magnet coil 1, and consequently the periods of time during which the relay coils 38 and 39 are energized and the corresponding 90 periods of time during which the resistance 65 in the field circuit of the exciter is not short-circuited will be varied in a similar manner.

It will be observed that in the upper extreme position of the stop 36 which it takes when the voltage applied to the main magnet coil 1 exceeds a certain predetermined limit the contacts 30 and 31 remain permanently in engagement, whereas in the extreme lower position of the stop 36 which occurs when the voltage applied to the main magnet coil 1 is below another predetermined limit the contact 31 will not be engaged by the contact 30. In the first case 105 the resistance 65 will always be included in the exciter field circuit whereas in the second case said resistance will be permanently short circuited.

It will be understood that variations may 110 be made in the device described without exceeding the limits of the invention, for instance, the relay magnet may be arranged to be short-circuited intermittently instead of its circuit being made and broken and suitable devices may be provided for obviating 115 sparking at various contacts.

What I claim is:

1. An electrical regulator comprising 120 cooperating main contact members, an arm carrying one of said members, an electromagnet for vibrating said arm at a substantially constant frequency, a pair of auxiliary contact members controlling the circuit of the said electromagnet one of which mem- 125

- bers is carried by the said arm, a second arm upon which the other main contact member is mounted, means normally tending to cause the main contact members to engage, a third arm for varying the position of the second arm, and means for governing the position of the third arm in accordance with variations of the quantity regulated.
- 10 2. An electrical regulator comprising cooperating main contact members, an arm carrying one of said members, an electromagnet for vibrating said arm at a substantially constant frequency, a pair of auxiliary contact members controlling the circuit of the said electromagnet one of which members is carried by the said arm, a second arm upon which the other main contact member is mounted, means normally tending to cause the main contact members to engage, a third arm for varying the position
- 5 of the second arm, means for governing the position of the third arm in accordance with variations of the quantity regulated, and means resiliently connected to, and retarding the operation of, the third arm. 25
3. An electrical regulator comprising cooperating contact members, means for vibrating said members into and out of engagement, means for controlling the position of one of said members in accordance with the value of the regulated quantity, and means resiliently connected to, and retarding the operation of, the latter means. 30
- In testimony whereof, I have hereunto 35
subscribed my name this tenth day of January 1913.

ALEXANDER HOLLEY OLMSTED.
